ABSTRACT OF THE DISCLOSURE

A fixture for holding a workpiece during an electrochemical drilling operation which is loaded by a mechanism that properly locates the workpiece in the fixture.

BACKGROUND OF THE INVENTION

Where electrochemically drilled holes are precisely located in a workpiece the latter must be precisely located on the machine in relation to the drilling electrodes. The locating surfaces are eroded away to some extent during each electrolytic drilling operation to such an extent that they shortly are not effective. It is essential to develop a system by which the workpiece will be precisely located for each operation regardless of the erosive action of the electrolyte and the electrochemical reaction.

SUMMARY OF THE INVENTION

One feature of the invention is a fixture in which the workpiece is precisely located with the fixture subsequently located in the electrochemical drilling machine. Another feature is the mechanism by which the workpiece will be located with the needed precision within the fixture.

According to the present invention, a locating mechanism has locating points for the fixture which points coincide in location with the locating points on the electrochemical drilling machine, and the mechanism also has precision locating elements by which the workpiece will be precisely located with respect to the fixture while the latter is securely mounted in the fixture. Since these locating points on the mechanism are separate from the drilling operation and thus not subject to an electrolytic action, these points will be effective over a long period, and will not cover areas on the part that are to be drilled.

BRIEF DESCRIPTION OF THE DRAWING

FIG. 1 is a side elevation of the mechanism and fixture in open position.

FIG. 2 is a view similar to FIG. 1 with the mechanism in closed position.

FIG. 3 is a front elevation of the structure of FIG. 1.

FIG. 4 is a plan view of the fixture in position on the base.

DETAILED DESCRIPTION OF THE PREFERRED EMBODIMENT

As shown in FIGS. 1 and 2, the fixture 2 is adapted to be positioned in an electrochemical drilling machine as described, for example, in the copending application of Andrews, Ser. No. 302,993 filed Nov. 1, 1972 and having a common assignee with this application. This fixture indicates a base 4 having an end edge 6, FIGS. 2 and 3 and opposed side edges 8 and 10 all serving as locating surfaces, as well as a bottom surface 12. This fixture is positioned on the locating mechanism base 14 which has a flat top surface 16 engaged by the surface 12 and cleats 18 and 20 secured thereto. Each cleat 18 and 20 has a surface 22 and 24 engageable by the end surface 6 and surfaces 26 and 28 engageable by the side surfaces 8 and

10, respectively. Clamps 30 and 32 hold the fixture base in position. It will be understood that the electrochemical drilling machine will have locating means thereon corresponding to the cleats 18 and 20.

5 The fixture base has two cups 34 and 36 thereon which receive portions of the workpiece 38, as for example, the shroud ends 40 and 42 on the turbine vane which is shown as the workpiece. The latter has an airfoil portion 44 between the shroud ends and this airfoil portion is to have 10 a plurality of holes 46 drilled in the trailing edge 48 thereof as shown by way of example in FIG. 2. It will be understood that these holes are shown by way of example and that such holes do not exist until this fixture with the vane thereon has been positioned in the drilling machine for the drilling operation.

15 The shroud ends are positioned in the cups and held securely therein by a suitable wax, or bedding compound 50, FIG. 3 which may be of any suitable self-hardening device that may subsequently be removed readily from 20 the shrouds.

25 For a precision location of the vane in relation to the fixture, the locating mechanism base 14 has a post 52 thereon on which is pivotally mounted a bracket 54 as by a pivot bolt 56. The bracket 54 includes a post 58 engaged by the pivot 56, a locating sub-base 60, and a clamp carrying arm 62. The sub-base has a pair of spaced 30 locating pins 64 and 66 for engaging the trailing edge of the airfoil portion of the vane at spaced points as shown. A supporting and locating stud 68 engages the vane along 35 its convex surface for further precision location of the vane.

40 The arm 62 carries a clamping arm 70 on a pin 71 having a clamp shoe 85 engaging the leading edge of the vane about midway of its length as shown in FIG. 3 and this arm is clamped in position by a toggle linkage 45 including a linkage arm 72 pivotally mounted on a pin 74 on a block 76 on the arm 62. This linkage arm 72 has a short actuating link 78 pivoted thereto by a pin 80 and pivoted on clamping arm 70 by a pin 82. A stop 84 limits the movement of arm 72 beyond the optimum clamping position shown to assure the workpiece 38 is firmly contacting locators 64, 66, 68 and 86.

45 The bracket 54 has a post 88 thereon in a position to engage the base 14 and support the bracket in the open position of FIG. 1. When the bracket is moved into the closed position of FIG. 2, the edge of the bracket 54 engages a fixed stop so that the locating sub-base 60 is held in precisely the position to locate the vane in the exact 50 relation to the locating surfaces on the fixture base.

55 When the mechanism is in the closed position of FIG. 2, the appropriate bedding compound is placed in the cups and the fixture remains in this position until the compound has solidified. Then, by releasing the clamping arm 72, the bracket is free to move out of the way of the fixture 60 and the latter may be released from the clamps 30 and 32. This fixture may then be placed in the electrochemical drilling machine for a drilling operation, being located therein by the same locating surfaces used in the locating mechanism. In this way the trailing edge of the vane will 65 be in the exact position for a drilling operation by the electrodes of the drilling machine. It will be noted that the fixture base has the locating surfaces 8 and 10 substantially at right angles to surface 6 and all of these surfaces are substantially at right angles to the bottom surface 12 and that those surfaces are substantially duplicated on the electrochemical drilling machine. These surfaces on the fixture and on the drilling machine are in contact during the drilling operation, and are remote from the zone of 70 action of the electrochemical drilling process so that no significant erosion action occurs on these surfaces and the locators do not cover areas on the part that are to be drilled.

I claim:

1. A fixture for locating a workpiece having spaced end elements by which the workpiece is to be held, said fixture including:
 a base having a plurality of locating surfaces thereon by which the fixture is located on a machine tool,
 a plurality of cups on said base spaced apart to receive portions of said end elements and in precise relation to the locating surfaces, and
 a bedding compound in said cups in which a portion of the end elements are embedded. 5
2. A fixture as in claim 1 in which the base has at least three locating surfaces substantially at right angles to one another. 10
3. A fixture as in claim 1 in which the workpiece has an airfoil portion with a trailing edge and this trailing edge is precisely located with respect to said locating surfaces. 15
4. A locating mechanism for precision location of a workpiece in a fixture including:
 a base having a plurality of locating surfaces for co-operation with similar surfaces on the fixture,
 a pivoted member having workpiece locating elements thereon and a workpiece clamping device said member having a loading position in which the workpiece is placed in the clamping device and a locating position, and 20
 a means for locating the pivoted member in locating position such that the locating elements are in precise relation to said locating surfaces, whereby a workpiece clamped in said member will be in precise relation to said locating surfaces. 25
5. A mechanism as in claim 4 in which the workpiece is a turbine vane having an airfoil portion with a shroud at each end and the locating elements are positioned to engage the trailing edge of the airfoil portion at spaced points. 30
6. A mechanism as in claim 5 in which the clamping device engages the leading edge of the airfoil portion of the vane near its mid-portion. 35
7. A locating mechanism for the precision location of a workpiece in a fixture said workpiece having spaced end elements by which the workpiece is held, the mechanism including:
 a base having a plurality of locating surfaces for co-operation with similar surfaces on the fixture,
 a pivoted member having workpiece locating elements thereon and a workpiece clamping device, said member having a loading position in which a workpiece 40
 45

is positioned in the clamping device and a locating position, and
 a means for locating the pivoted member such that in locating position the locating elements are in precise relation to said locating surfaces, whereby a workpiece clamped in said member will be in precise relation to said locating surfaces,
 in combination with the fixture, the latter having
 a base having a plurality of locating surfaces cooperating with the surfaces on the mechanism base,
 a plurality of spaced cups on the base of the fixture to receive the end elements of the workpiece, and
 a bedding compound in said cups in which the end elements are embedded and held therein by the solidification of the bedding compound.
 8. A device as in claim 7 in which the base of the locating mechanism has clamps to engage and hold the fixture in position.
 9. A device as in claim 8 in which the fixture is releasably positioned in the mechanism and is adapted to be similarly located in a machine with the workpiece thereon.
 10. A device as in claim 7 in which:
 the workpiece has an airfoil portion with end shrouds, and with the airfoil portion in engagement with the locating elements and the clamping device and in which the workpiece is held in said fixture by end portions of the shrouds embedded in the bedding compound in the cups in such a position that the trailing edge of the airfoil portion is in precise relation to the locating surfaces on the fixture base.
